CLAIM

USPC **D24/190**; D15/199

The ornamental design for a wearable robot, as shown and described.

(58) **Field of Classification Search**

DESCRIPTION

USPC D3/5, 6, 7, 8, 9, 10; D15/199; D24/164, D24/190

FIG. 1 is a front perspective view of a wearable robot showing our new design;

CPC A61F 5/0102; B25J 9/104; B25J 9/106; B25J 9/109; B25J 9/0006; B25J 17/0241; B25J 19/02; Y10T 74/20317; Y10T 74/20323

FIG. 2 is a front view thereof;

See application file for complete search history.

FIG. 3 is a rear view thereof;

(56) **References Cited**

FIG. 4 is a left side view thereof;

U.S. PATENT DOCUMENTS

FIG. 5 is a right side view thereof;

5,690,609 A 11/1997 Heinze, III
D494,273 S 8/2004 Haugland
D749,227 S 2/2016 Takama
D784,547 S 4/2017 Kwon
D851,387 S 6/2019 Chavarria
D901,023 S * 11/2020 Park D24/190

FIG. 6 is a top plan view thereof;

FIG. 7 is a bottom plan view thereof; and,

FIG. 8 is a rear perspective view thereof.

The dashed broken lines in the figures illustrate portions of the wearable robot that form no part of the claimed design. The dot-dash broken lines in the figures define boundaries of the claimed design and form no part of claimed design.
